FLUORESCENT LAMP

Jefferson E. Gates, Jacksonville, Fla.

Application March 19, 1941, Serial No. 384,172

1 Claim. (Cl. 176—124)

This invention relates to fluorescent lamps of that type which is adapted to be screwed into the conventional threaded light socket.

Fluorescent lamps have come into rather widespread use because of their superior illuminating qualities, as well as their low power consumption relative to the incandescent lamp. Such use has been largely confined to commercial and public establishments, rather than to private homes. This has been due to the expense of installation, as such lamps require special sockets, ballast in the form of transformers and the like, and other equipment. A further reason for the lack of popularity for home use is the fact that fluorescent lamps have been made in the form of tubes, these tubes varying in length in accordance with the output of the lamp.

The present invention has for its object the provision of a fluorescent lamp provided with an adapter, whereby the lamp may be attached to the conventional light socket, the adapter housing the necessary ballast and starter units.

Another object of the invention is to provide such a lamp which may be readily secured to or removed from the adapter without removing the adapter from the socket in which it is threaded.

A further object of the invention is to provide a fluorescent lamp, in which the distance that the electrons must travel from one electrode to the other is greatly reduced in proportion to the total amount of phosphor bearing surface area of the lamp, resulting in low brightness per unit area of surface and a high total light output with low power consumption.

A still further object of the invention is to provide such a lamp having an improved starting means to preheat the lamp electrodes to provide an abundance of free electrons, and to heat the mercury vapor within the lamp before and after the high voltage starts normal lamp operation.

Other objects will appear as the following description of a preferred and practical embodiment of the invention proceeds.

Referring to the drawing:

Figure 1 is a vertical section illustrating the improved lamp and adapter;

Figure 2 is a horizontal section on the line 2—2 of Figure 1, illustrating the socket for receiving the lamp;

Figure 3 is a section on the line 3—3 of Figure 1, showing the pins on the end of the lamp;

Figure 4 is a wiring diagram of the circuit for controlling the lamp, in which the auxiliary heater switch is automatic; and

Figure 5 is a similar diagram, in which the auxiliary heater switch is manually controlled.

Referring to the drawing in detail, in Figure 1 is shown a fluorescent lamp having a glass bulb 1 of substantially globe shape. The bulb 1 is provided with a neck 2 having an annular shoulder 3 upon which is seated a disk 4 of suitable insulating material. The glass is molded over the top of the disk to securely position the disk in place.

The disk 4 forms a base upon which the interior elements of the lamp are supported, and also carries the base pins 5. Hollow glass tubes 6 extend from the disk 4 and support, at their lower ends, a second disk 7. Positive and negative electrodes 8 and 9 are fastened to the disks 4 and 7, respectively, and wires 10 connected to the base pins 5 extend through the tubes 6 to supply current to the electrode 9.

The electrodes 8 and 9 are in the form of small rods of wire, coated with a material which has the property of freely emitting electrons when heated. The electrodes are secured upon the disks in circular form, and the electrons in passing from one electrode to the other will form a cylindrical curtain between the disks.

It can be readily seen that through the use of a globe-shaped bulb with the electrode arrangement of the present invention, a great amount of surface area on the bulb is secured with only a relatively small distance between the electrodes. The less distance the electrons are required to bridge, the less power necessary to make the arc. The circular form of the electrodes, and the consequent cylindrical curtain of electrons produced thereby, will cause the mercury vapor within the bulb to activate a greater number of phosphors, with which the interior of the glass bulb is coated, than will the conventional relatively thin arc.

In order to adapt the lamp for use with present day light sockets, an adapter 11 is provided comprising a housing 12, preferably moulded from a plastic, and having a threaded plug 13 to fit a conventional light socket. The housing 12 is cup-shaped to receive a transformer 14 and a thermal switch control 15. Screws 16 hold the transformer within the housing. A skirt 17 is fastened to the underside of the transformer casing, and forms a socket to receive the base of the bulb. Bayonet slots 18 are provided in the skirt to receive pins 19 extending from the base of the bulb to lock the bulb in place in the adapter. A partition 20 separates the socket into two compartments and is provided with arcuate slots 21 to receive the base pins 5 of the bulb. Se-

cured to the partition 20 in such position that the ends of the base pins 5 of the bulb will engage them when the bulb is in place in the socket and the pins protrude through the slots 21, are the spring contact fingers 22. The various wires from the transformer and the thermal switch are connected to the spring contact fingers, and current is transmitted from the fingers to the elements within the lamp bulb through the base pins 5. An apron 22' is secured to the housing and extends downward, its lower edge being in close proximity of the bulb, to give a finished appearance to the entire unit and to hide the socket and various connections when the bulb is in place.

Referring to the wiring diagram shown in Figure 4, the thermal control switch 15 is shown in the position it will assume when there is no current passing through the lamp. The switch consists of two electrodes, the fixed electrode 23 and the electrode 24 which is made from a bi-metallic strip. These are separated under normal conditions and form part of a series circuit through the lamp electrodes 8 and 9 and the ballast 14 which may be a high reactance transformer or reactor. This circuit is as follows: from the source of power through wire 25, ballast 14, wire 26, lamp electrode 8, wire 27, switch bi-metallic electrode 24, switch fixed electrode 23, wire 28, lamp electrode 8, wire 29 to the opposite side of the power supply. When voltage is applied to the circuit, no current flows except as a result of the glow discharge between the two electrodes of the switch. A heating results which, by the expansion of the bi-metallic element, causes the electrodes to touch. This short circuiting of the switch, which takes one or two seconds to be completed, allows a substantial flow of current to preheat the lamp electrodes. There is enough residual heat in the switch to keep it closed for a short additional time, a suitable period under normal conditions to preheat the lamp electrodes. With the opening of the switch, the resultant high voltage surge starts normal lamp operation.

The switch does not again glow, since it is so designed that the remaining available electrical potential is insufficient to cause a breakdown between the electrodes. This switch, and its operation, is well known in the art, and is usually referred to as a "glow switch."

Frequently, when fluorescent lamps are used out of doors in cold weather, the preheating of the lamp electrodes in the period of time allowed by the control switch is insufficient to warm the mercury vapor within the bulb and the arc fails to strike. To overcome this difficulty, the present invention provides a small heating coil 30, located within the bulb and receiving its current from a secondary winding 31 on the transformer 14. The heating coil is controlled by the thermal control switch, and is connected thereto by means of an additional contact 32 and the following circuit: contact 32, wire 33, secondary coil 31, wire 34, heating coil 30, wire 27, and switch bi-metallic electrode 24.

When voltage is first applied, the bi-metallic electrode is in contact with the contact 32, and the heating coil is energized to give an initial

heating to the interior of the bulb. When the electrode 24 has moved from the contact 32 to make contact with the electrode 23 the circuit through the heating coil is broken. After the preheating of the lamp electrodes, the bi-metallic electrode 24 again makes contact with 32 and the heating coil is again energized to maintain the temperature within the bulb to the point for most efficient operation of the lamp. A resistance 35 is tapped onto the heating coil circuit to prevent current build-up within the secondary coil and subsequent burning out of the coil.

The operation of the heating coil as described above, is entirely automatic, but in Figure 5 is shown a circuit employing a manually controlled heating coil. In this layout a manually operated switch 36 may be thrown to either the contact 37 or the contact 38, and when the switch is in contact with 37 the heating coil is in operation and the circuit is: switch 36, wire 39, secondary coil 31, wire 40, wire 26, lamp electrode 8, wire 27, heating coil 30, wire 41, and contact 37. When the switch arm 36 is in contact with 38, the heating coil is no longer energized, but a circuit is set up from switch arm 36 through wire 39, secondary coil 31, resistance 42 to contact 38. This circuit is set up to prevent a build-up of the induced current in the coil 31. It will be readily understood that in this form of the invention the heating coil operates continuously, so long as the switch arm is in contact with the contact 37.

While I have in the above described preferred embodiments of the invention, the invention is not to be considered as limited to the forms shown and described, but only by the scope of the appended claim.

What I claim as my invention is:

An adapter for detachable connection with a fluorescent lamp containing a heater and with an ordinary electrical outlet socket for connecting such a lamp with such a socket, said adapter comprising an article of manufacture separate from the lamp and lamp socket and embodying a housing having a chamber therein opening through one side thereof, a plug carried by the housing for connection with the socket, a transformer including a secondary coil for energizing the heater in the lamp, said transformer also acting as a ballast, and a thermal control switch to control the operation of said heater arranged in the chamber of the housing, a socket projecting from the transformer and exposed at the open side of the housing and adapted to receive a part of the lamp when the adapter is connected with the lamp, said socket in the housing having locking means engageable with and disengageable from coacting locking means on the lamp to lock the adapter to or unlock it from the lamp, circuit connections within the housing between the plug, transformer and thermal control switch for establishing an electric circuit, and spring contacts arranged within the transformer socket for engagement with and disengagement from conductors carried by the lamp when the adapter is connected with and disconnected from the lamp.

JEFFERSON E. GATES.
